Filed Nov. 27, 1967, Ser. No. 9,554

Term of patent 14 years

(Cl. D83—1)

FIGURE 1 is a front perspective view of a monitor for intravenous feeding systems or the like embodying my new design;

FIGURE 2 is a top plan view of the monitor shown in FIGURE 1;

FIGURE 3 is a rear elevational view of the monitor shown in FIGURE 1;

FIGURE 4 is a right side elevational view of the monitor shown in FIGURE 1; and

FIGURE 5 is a bottom plan view of the monitor shown in FIGURE 1.

The dominant features of my design reside in the portions shown in full lines.

I claim:

The ornamental design for a monitor for intravenous feeding systems or the like, as shown and described.
